UNITED STATES PATENT OFFICE.

JOHN SELLERS BANCROFT, OF PHILADELPHIA, PENNSYLVANIA, ASSIGNOR
TO WILLIAM SELLERS, OF SAME PLACE.

MACHINE FOR POINTING DRILLS.

SPECIFICATION forming part of Letters Patent No. 337,549, dated March 9, 1886.

Application filed May 1, 1884. Serial No. 129,923. (Model.)

To all whom it may concern:

Be it known that I, JOHN SELLERS BANCROFT, of the city and county of Philadelphia, and State of Pennsylvania, have invented certain new and useful Improvements in Machines for Pointing Drills, of which the following is a specification.

In all drills there is necessarily a certain thickness of metal left between the two sides of the drill to hold them together—as, for example, the web left between the two spiral grooves in a twist-drill—and hence the two cutting-edges do not meet, and the line which connects them, formed at the intersection of the two surfaces to which the lips are ground, is the so-called "point" of the drill. The thickness of the point is the length of this line and varies with thickness of the metal in the center of the drill and the amount of clearance given to the lips. This point offers great resistance to the progress of the drill through the work on account of the very obtuse angle at which the surfaces forming the point meet, thus making the action at this line of junction rather one of scraping than of cutting, and of course the resistance increases as the thickness of the point is increased with the size of the drill. With large drills the thickness of this web to give the required strength to the lips is so great that it has long been recognized as necessary to reduce the point by grinding it away, so that the two flat sides of a flat drill, or the two concave sides of a twist-drill, will converge more rapidly toward the point. This grinding, or "pointing," as it is technically termed, has prior to my invention been performed exclusively by hand, without the aid of machinery other than a revolving grinding wheel or stone. When so performed, however, it requires great care for the most expert workman to thin the point so that it will be even approximately central between the two cutting-edges of the drill.

In the patent granted to J. Sellers Bancroft, this applicant, and Wm. H. Thorne for a machine for sharpening drills, No. 270,365, dated January 9, 1883, means are shown and described for grinding the lips of a drill so that the two cutting-edges shall be exactly the

same angle with and equidistant from the axis of the drill, and the apex of the convex point so produced will be exactly on this axis; but if the metal forming the web of the drill is not central one cutting-edge will be longer than the other; hence the two cutting-edges would not work exactly alike and the size of the hole would be uncertain. It has therefore been found necessary for accurate work to point the drills after they have been thus sharpened.

It is the first object of my invention, therefore, to point a drill so that the axis of rotation, from which the two cutting-edges are equidistant and about which they revolve at the same angle of inclination, shall be exactly in the center of the above-defined point of the drill, and the point itself shall be of the minimum practical thickness.

It is a further object of my invention to hold the drill to be pointed accurately in its true position without depending upon exceptional skill on the part of the operator; and to these ends the nature of my invention consists in mechanism for chucking and clamping the drill so that I am enabled to grind away each side of the point of the drill or reduce the point by forming on each side of the point a surface inclined to a plane passing equidistant from and between the two cutting-edges, these surfaces being also equidistant from the axis of the drill; and it further consists in mechanism for automatically conforming the width of the surfaces to the diameter of the drill to be pointed.

In the accompanying drawings, which form part of this specification, Figure 1, Sheet 1, represents an elevation of my invention with the jaws for holding the drill removed so as to show the grinding-wheel in contact with the drill. Fig. 2, sheet 2, is a plan showing a drill in position in the jaws. Fig. 3 is an enlarged plan of the jaws for holding the drill. Fig. 4 is an elevation of part of Fig. 3, showing the means for guiding the jaws. Fig. 5, Sheet 3, is an elevation of Fig. 3, showing the stops on the jaws for accurately determining the position of the drill to be pointed. Fig. 6 is a plan of the wheel holding and guiding mech-

anism shown in position for pointing the smallest drill for which the machine is calculated. Fig. 7 is an end elevation of part of Fig. 6. Fig. 8 is a plan of the parts shown in Fig. 6 in position for pointing the largest drill the machine is calculated to grind. Fig. 9 is a projection of the grinding-wheel on a plane passing through the center of the wheel and at right angles to its path when the wheel holding and guiding mechanism is in the position shown in Fig. 8. Figs. 10 and 11, Sheet 1, are side and end views, respectively, of a twist-drill pointed by my improved machine. Figs. 12 and 13 are side and end views, respectively, of a flat drill pointed by the same means.

In all the figures similar letters refer to similar parts.

The operation is the same whether the drill operated upon is flat or twist.

The drawings show the machine about one-half size.

A, Figs. 1 and 2, represents the bed of the machine.

B, Fig. 2, Sheet 2, shows a drill in position for pointing. The back end of the drill is carried by the sliding back center, D, which slides freely on the rod C, secured in the stand A. The center D is retained in alignment by a feather sliding in a groove in the rod C, and is clamped by the nut S, so as to steady the end of the drill B, which is held firmly against the center D after its longitudinal position has been fixed by the end stop, n, hereinafter described. When the drill is turned over to have the other side of the point ground, it is held firmly against the center D while reclamping the cutting end. The cutting end of the drill is clamped between the faces o and p on the jaws E and F, the drill being first rotated by hand until its lips rest against the stops l and m on the jaws F and E, respectively, in which position it is retained by the hand of the operator during the process of grinding, (see Figs. 3 and 5,) the longitudinal position of the drill being determined, as above mentioned, by the end stop, n, on the jaw E, so that the drill is accurately chucked or clamped in position radially by the clamping-faces o and p, circumferentially by the stops l and m, and longitudinally by the end stop, n. The corner formed by the meeting of the two faces o and n is so located near the axis of the cylindrical part of the jaw E that it will always move in the same line relatively to the guiding-slot in the block G without being affected by the angle at which this block may be clamped.

To locate the reduced point of the drill between the two cutting-edges, so that these edges shall be equidistant from it and of equal length, it is essential that the cutting-edges shall be held accurately, so that the outer ends of the cutting-edges shall be equidistant from the axis about which they revolve, and so that these ends and the axis of the drill shall be in the same fixed plane, and in the same position longitudinally when either side of the point,

as above defined, is presented to the grinding-wheel.

It will be observed that any method of grasping the body of a drill in a chuck or laying the drill in the groove for the purpose of pointing is undesirable, first, because these methods would be applicable to twist drills only; and, second, because it is impossible by such methods of holding to be certain that the point will be central between the two cutting edges, since any crookedness in the drill or irregular spacing of the flutes will vary the position of the end of the drill as it is turned over in the chuck. It is consequently essential for the accurate location of the reduced point that the drill should be held by the outer ends of the two cutting-edges, and these cutting-edges, or the edges of the flutes immediately adjoining these cutting-edges, should be held against stops—such as l and m—to fix their position relatively to the grinding-wheel—that is to say, the drill should be held or chucked radially and circumferentially with reference to its cutting-edges. If the drill is thus held or chucked and the grinding-wheel is brought to bear upon the point so as to reduce it slightly, and the drill is then turned half-way round (being held against the back center, D, to prevent longitudinal motion, the end stop, n, being used only to determine the position of the drill when first chucked) and again grasped by the same surfaces, and the grinding-wheel again brought to bear upon the reversed point without any change in the adjustment of the wheel, it will result in the point being absolutely central between the two cutting-edges.

It will be evident that, instead of the back center, D, the end stop, n, may be used to determine the position of the drill in both chucks; but this requires that the back center, D, shall be held against the drill by a spring or its equivalent to prevent side motion on the conical center.

The clamping jaws E and F are made cylindrical on their clamping ends, which are supported by the blocks G and H, as shown in Figs. 3, 4, and 5, the clamping-faces o and p and stops l, m, and n being formed on the upper ends of these cylinders, while the lower ends slide in slots h and j in the guiding-blocks G and H. These slots or grooves confine the motion of the jaws in right lines laterally, while the enlarged portion of the arms of the jaws fit in grooves a and b, which prevent vertical motion of the jaws. These cylindrical ends of the jaws E and F, in connection with the pivot-screws c and d in the lever N, leave free the angular adjustment of the blocks G and H without in any manner interfering with the bearing and support of the jaws in the blocks. The jaws E and F are moved in and out to grasp a small or large drill by means of the lever N, pivoted at T, Fig. 2. The short arms of this lever are of equal length, and the arms of the jaws E and F are attached thereto

by the pivot-screws *c* and *d*, respectively, so as to vibrate freely about these screws. When the lever *N* is vibrated about the center *T*, the jaws *E* and *F* are simultaneously and equally moved to or from the center line of the drill *B*. It is essential that the points of the drills to be ground should always come in the same position relatively to the path of the grinding-wheel, and therefore the jaws *E* and *F* must move in lines parallel with the cutting edges of the drill, and, as the angles which these edges make with each other may be varied according to the nature of the work to be performed, the guide-blocks *G* and *H* are made adjustable about the center *e*, as shown in Fig. 3, and their inner edges are set to correspond with the proper graduations on the base-plate to conform to the angle of the drill lips, the bolts *f* and *f'* (shown in dotted lines) being used to clamp the blocks in the desired position. These blocks should be adjusted so that the slots *h* and *j*, which guide the cylindrical portion of the jaws, shall be parallel to the cutting edges of the drill *B*. The center line of these slots *h* and *j* is radial to the center *e*, about which the blocks *G* and *H* rotate, and the centers of the cylindrical portion of the jaws will therefore move in radial lines, and hence all drills, of whatever diameter within the range of the machine whose cutting-edges are at the same angle as that to which the blocks *G* and *H* are set will have their respective points brought to exactly the same position relatively to the path of the grinding-wheel. The grinding-wheel *I* travels in a circular path that has for its radius the link *M* and for its center the pivot *U*. The axis of the pivot *U* being inclined, as shown in Fig. 1, the line of motion of the wheel *I* is at a considerable angle with the axis of the drill, as indicated by the line *y y*, Fig. 1, so that the greatest depth of the cut made by the wheel will be at the extreme end of the drill, this cut rapidly decreasing in depth as it extends back from the extreme end, and hence the supports to the cutting-edges of the drill are not weakened by thinning the center, as is usually the case in hand-grinding. The path of the cutting-line of the wheel is indicated by the line *y y* in Figs. 2 and 3, and it will be seen that it passes between the line of the axis of the drill and its cutting-edge. The wheel *I* is secured on one end of a mandrel, which turns freely in the bearing *J*, and is driven by the cord-pulley *V*, secured to the opposite end. The belt driving this pulley *V* passes under the fixed pulley *W*, and also under the tightener-pulley *X*, carried by the weighted arm *Y*, which is pivoted at *Z*. The path of the belt is indicated by broken lines in Fig. 1. The tightener-pulley accommodates the belt to the varying position of the pulley *V*. The vibrating frame *L* is supported so as to swing freely on the pivots *U* and *k*, fastened in a stand formed with or secured to the bed *A*, the axes of the pivots *U* and *k* being in the same axial line and in-

clined to a horizontal plane, as shown in Fig. 1, for the purpose above described. The frame *K* is pivoted on the vibrating frame *L* by pivots *g* and *r*, which are parallel with the pivots *U* and *k*. The other end of the frame *K* carries the adjustable rod *s*, to which is secured the bearing *J*, as shown in Fig. 7, Sheet 3. The rod *s* is provided at its upper end with a screw-thread, which engages with the adjusting or feed nut *t*, which regulates the height of the wheel *I* by sliding the rod *s* through its bearings in the frame *K*. The nut *t* is graduated on its circumference, so that the grinding-wheel may be set to the same distance from the axis of the drill for each side of the point, the same graduation being made to coincide with the mark or index *z'* on the index-link *R*. The pivot *u* is secured firmly in the bearing *J*, so that its axis, if prolonged, would intersect the axis of the grinding-wheel at a right angle, and pass through the point in its circumference, where it touches or is tangent to the drill to be ground. This pivot *u* turns and slides freely in the radius-link *M* and index link *R*. From this combination it follows that the point of tangency of the wheel with the drill will always move in a fixed path, determined by the length of the radius-link *M* and the position of the fixed pivot *U*. The frame *K* and radius-link *M* are of equal length. The distance between the rod *s* and pivot *u* is equal to the distance between the pivots *U* and *r*, and this method of carrying the grinding-wheel thus forms a parallel motion, and, as the rod *s* is parallel to the pivot *u* and in the plane of the grinding-wheel, it follows that the wheel *I* will remain parallel to a plane passing through the pivots *U* and *r* in all parts of its path. In Fig. 6 these parts are shown in position for pointing the smallest drill for which the machine is adapted, the broken line *y y* showing the path of the pivot *u* and of the corresponding point of tangency of the wheel *I* with the drill. The line *z z* shows the path of the rod *s*. In this case it will be observed that the cut made by the wheel *I* will be but little wider than the thickness of the wheel itself, as when the wheel is at the extreme end of the drill its center plane is tangent to the path described by the pivot *u*, and the cut made in the drill will be wider than the wheel only by the amount of the versed sine of the arc through which the wheel swings while in contact with the drill. A cam, *P*, on the inner end of vibrating frame *L* is pressed against a boss, *O*, on the lever *N* by a spiral spring, *w*, which rotates the lever *N* in the direction to close the jaws *E* and *F*, and hence grips any drill held between the jaws with a force due to the strength of the spring *w*. In Fig. 6, Sheet 3, the boss *O* is shown in contact with the cam *P* in the proper position for the smallest drills the machine is calculated to grind, the broken circle *O'* showing the position of the boss *O* when the largest drill the machine is intended to grind is clasped between the jaws. In Fig. 8 the cam *P* is shown

as moved over to this position, thereby moving the vibrating frame L through an angle of about fifteen degrees, the effect being to swing the axis of the grinding-wheel I through 5 the same angle about the pivot *u* in a plane parallel with the path in which its grinding-surface operates without changing the position of the pivot *u*, which still describes the same arc *yy* about the fixed center U, and consequently the point of tangency of the wheel with the drill also moves in the same path as before. The pivot *r* being shifted by the movement of the vibrating frame L, the rod *s* describes the path *zz* about this new position, so the center plane of the wheel is still parallel to the plane passing through the pivots U and *r*, and the profile of the wheel relatively to its path at the point of the drill is represented in Fig. 9, so the cut made in the 10 point by the wheel will now be much wider than before.

By properly proportioning the cam P and lever N it is possible to vary the angle of the axis of the wheel I in a plane parallel to the path in which its grinding-surface operates to 15 any desired extent proportioned to the size of the drill to be pointed, and when this position is once determined in the construction of the machine, the operator has only to see that the blocks G and H are set to the angle to which the drill-lips are ground, after which the operation of clasping the drill between the jaws E and F by means of the clamping-lever N automatically adjusts the grinding-wheel to 20 the proper angle. The spiral spring *w*, through the pressure of the cam P against the lever N, tends to hold the jaws E and F against the drill. The back center, D, is now moved up so as to hold the end of the drill, and the operator, placing his hand on the radius-link M, moves the wheel I back and forth over the 25 point of the drill B, the amount of cut at each stroke being adjusted by the feed or adjusting nut *t*. When one side is properly pointed, 30 the lever N is pushed back so as to open the jaws, the drill is turned over, the lips coming against the stops *l* and *m*, as before, and the wheel is passed over this side of the point of the drill until the graduation on the adjusting- 35 nut *t* is at the same mark as before, when the surfaces on each side of the point will be at 40 exactly the same distance from the axis of the

drill, and consequently the chisel edge or point will be central, and the drill thus pointed, assuming that its lips have been properly 45 ground, will produce accurate work.

In the foregoing description the traverse of the grinding-wheel has been described as being in a circular path of comparatively short radius. The length of this radius is not essential, as it may be extended indefinitely, it being requisite only that the grinding-surface of the wheel should be guided in a fixed path, the width of the path being varied by adjusting the axis of the wheel in a plane parallel to 55 the path in which its grinding-surface operates.

Having now described my invention, what I claim as new, and desire to secure by Letters Patent, is—

1. In a drill-pointing machine, a grinding-wheel operating in a fixed path with its axis variable in a plane parallel to the path in which its grinding-surface operates, whereby the width of the path may be increased or diminished, substantially as and for the purpose set forth. 70

2. In a drill-pointing machine, the combination of a grinding-wheel, a supporting frame therefor vibrating about an axis perpendicular to the axis of the grinding-wheel, drill-clamping jaws, and a lever connected to said jaws and engaging said wheel-carrying frame, whereby the movement of the lever to operate the clamping-jaws adjusts the wheel-carrying frame with relation to the jaws and varies the width of the path of travel of the grinding-wheel to correspond to the size of the drill held by the clamping-jaws. 85

3. In a drill-pointing machine, clamping-jaws for holding the drill, in combination with supports which guide the clamping-jaws in lines parallel to the cutting-edges of the drill, substantially as and for the purpose set forth. 90

4. The adjustable guiding-blocks G and H, in combination with the clamping-jaws E and F for holding the drill, whereby the movements of the clamping-jaws are made parallel to the cutting-edges of the drill, substantially as and for the purpose set forth. 95
